UNITED STATES PATENT OFFICE.

JOHN B. VAN ZANDT, OF NEW YORK, N. Y.

COMBINED CANE AND BURGLAR-ALARM.

SPECIFICATION forming part of Letters Patent No. 292,389, dated January 22, 1884.

Application filed November 19, 1883. (No model.)

To all whom it may concern:

Be it known that I, JOHN B. VAN ZANDT, of New York city, in the county of New York and State of New York, have invented certain new and useful Improvements in a Combined Cane and Burglar-Alarm; and I do hereby declare that the following is a full, clear, and exact description of the invention, which will enable others skilled in the art to which it applies to make and use the same, reference being had to the accompanying drawings, and to the letters of reference marked thereon, which form a part of this specification.

This invention has for its object to provide the handle of a cane of such construction as to adapt the cane for use as a detonating burglar-alarm, whereby the occupant of a room may be aroused from sleep in an attempt being made by unauthorized persons to gain access to his apartment.

To this end the invention consists in such details of construction and combination of parts as will be hereinafter distinctly pointed out.

Referring to the drawings hereunto annexed, Figure 1 represents the manner in which the cane is suspended over the top of a door, and how, when the door is opened, it is made to descend by gravity and produce an alarm. Fig. 2 is a vertical sectional view of the handle of the cane to show its construction, and Fig. 3 is a view of devices forming the means of suspension for the cane.

The cane is in all respects similar to an ordinary walking-stick, with the exception of the handle and ferrule. The handle consists of a collar secured to the upper end of the cane, and within which is located a small screw-threaded nut. At the end of the collar is placed a thimble, which is held on by a screw passing down through it and through the nut aforesaid, which is located within the collar. The upper end of the thimble is concave, and the head of the screw is inclined inward from the top thereof, to thus conform to the contour of the said concaved end of the thimble, into which it fits. When the screw is screwed down, the inclined face of the head thereof rests against the corresponding face around the inner edge of the concavity in the thimble. Between these two

faces it is proposed, when desired, to place a small percussion-cap, so that an alarm may be produced by striking the head of the cane sufficiently hard to explode the cap. The ferrule is provided on opposite sides with small holes for receiving the ends of a spring-clamp, by which the cane is suspended.

Referring to the letters of reference, A represents the cane, and B the handle as a whole.

C is the collar, which is suitably secured around the upper end of the cane, said cane being hollowed out for a short distance to admit of the end of the screw.

c indicates the screw-nut in the collar; d, the screw, whose head is inclined on its under side; and e represents the thimble having the concaved end, into which the screw-head fits.

D represents a device by which the cane is suspended. It consists of a piece of wire, f, having linked to one end a spring-clamp, g, whose ends fit into holes on opposite sides of the ferrule of the cane. This wire is so bent that when placed in the space or crevice between the upper edge of the door and frame the weight of the cane will be sufficient to maintain it (the cane) steady. This spring-clamp could be carried in the pocket on an ordinary key-ring, and readily detached therefrom when needed.

The operation is as follows: The occupant of the room simply takes the cane and suspends the same over the top of the door, as hereinbefore explained. On the door being slightly opened the support for the cane is released, whereupon the cane drops and, striking the floor, explodes the cap, thus frightening away the thief and arousing the occupant of the room.

What I claim is—

1. In a combined cane and burglar-alarm, the combination of the cane with the collar C, thimble e, and screw d, all substantially as described.
2. The combination of the cane having collar, as described, and the screw-nut located in said collar, with the thimble e and screw d, said thimble being formed at its upper end for the reception of the screw-head, substantially as set forth.
3. In a combined cane and burglar-alarm,

the cane having handle constructed substantially as described, and having ferrule provided with holes in its side, in combination with the means whereby the cane is suspended, as set forth.

4. An attachment for canes, umbrellas, and the like, composed of the collar, the screw-nut located therein, the thimble *e*, and screw *d*, all constructed and combined substantially as set forth.

In testimony that I claim the foregoing as my own I affix my signature in presence of two witnesses.

JOHN B. VAN ZANDT.
